UNITED STATES PATENT OFFICE

169,142

COMBINED SPARK PLUG AND SHIELD
THEREFOR

Maxwell Ingram, Dumont, N. J.

Application June 9, 1950, Serial No. 10,441

Term of patent 14 years

(Cl. D26—1)

To all whom it may concern:

Be it known that I, Maxwell Ingram, a citizen of the United States, residing at No. 15 Hamilton Avenue, Dumont, New Jersey, have invented a new, original, and ornamental Design for a Combined Spark Plug and Shield Therefor, of which the following is a specification, reference being had to the accompanying drawings, forming part thereof.

Figure 1 is a front elevation of the combined spark plug and shield therefor showing my new design.

Figure 2 is a front elevation of the shielded spark plug showing the cover and body portion thereof separated from each other.

Figure 3 is a top plan view of the shielded spark plug, and

Figure 4 is a side elevational view thereof.

I claim:

The ornamental design for a combined spark plug and shield therefor, substantially as shown.

MAXWELL INGRAM.
